Patented Jan. 13, 1925.

UNITED STATES PATENT OFFICE.

ERNEST VAN TOFF, OF CHICAGO, ILLINOIS.

ROTARY FAN FOR AUTOMOTIVE VEHICLES.

Application filed January 14, 1922. Serial No. 529,132.

To all whom it may concern:

Be it known that I, ERNEST VAN TOFF, a citizen of the United States, and a resident of the city of Chicago, in the county of Cook and State of Illinois, have invented certain new and useful Improvements in Rotary Fans for Automotive Vehicles, of which the following is a specification.

This invention relates to improvements in rotary fans for cooling internal combustion engines, the shafts for which are provided with fly wheels distantly located from their fan as distinguished from fans particularly designed to be used as a fly wheel for said engines.

The object of my invention is to provide the usual fly wheel of an engine with a fan surrounding and mounted upon said fly wheel for transmitting the heat from the engine and directing it in a plane substantially parallel to the axis of the fan.

Another object is to provide a means for reducing to a minimum, as nearly as may be, the resistance of the cooling fan to the passage of the hot air currents from the engine and also for reducing the volumetric losses of the air during and after the discharge of the air by the fan from the engine; in other words, a means substantially directing the heated air currents from the engine to the fan and from the fan in a plane substantially parallel with the axis of the fan for thereby accordingly reducing any pressure of the air otherwise tending to retard the movement of the fan.

With these ends in view, my invention finds embodiment in certain features of novelty in the construction, combination and arrangement of parts by which the said objects and certain other objects are attained, all as hereinafter fully described with reference to the accompanying drawings and now particularly pointed out in the claims.

In said drawings:—

Fig. 1 is a perspective view of an automotive vehicle, with parts broken away for disclosing the supporting frame providing a housing for the fan.

Fig. 2 is an enlarged detail vertical section through the fly-wheel and the fan, for illustrating the latter and the housing therefor.

Fig. 3 is a longitudinal section taken on the line 3—3 of Fig. 4.

Fig. 4 is a top plan view of the front portion of the vehicle.

Fig. 5 is a vertical section taken on the line 5—5 of Fig. 3; and

Fig. 6 is a vertical section taken on the line 6—6 of Fig. 3.

Similar characters of reference indicate the same parts in the several figures of the drawing.

In carrying out my invention, the frame for supporting the body 7 of the vehicle consists (see Fig. 1) of side bars 8, 8 and a cross-bar 9, (see Fig. 3), which side bars, at their forward ends, are bolted to a frame 10, constituting the front end of the frame of the vehicle, which frame 10 is bent from a metal plate to form side bars 11, 11, connected at their forward ends by a cross-bar 12, and which, for strength, form a channel beam in cross-section, from which plate is also bent a two-part housing 13, for a fan, the vanes of which are secured to the fly-wheel for the engine, said housing being provided with projecting segmental flanges 14 and radially with flanges 15 secured together by means of bolts or rivets 16.

This metallic frame (see Fig. 4) constitutes the support for the engine 13^a located and secured thereto by means of brackets 14^a, as heretofore, and for the transmission 15^a of the vehicle by means of brackets 16^a, the bolts 17 for which pass through the wooden side bars 8 and the side bars 11, 11 of the metal frame, the wooden side bars being confined between the flanges thereof.

The metallic frame (see Fig. 1) is supported on the front axle 18 of the vehicle, as shown, by means of springs 19, indicated by dotted lines, connected with the frame by means of depending hangers 20 riveted thereto, and the body of the vehicle by means of springs 21, secured at one end to a shaft 22, having its bearings in hangers 23 at each end thereof, which springs 21 are secured as usual, at their other end, to the rear axle 24 of the vehicle.

Centered on the rear-end crankshaft 25 is the fly-wheel 26, which is secured to the shaft by means of bolts 27, passing through the fly-wheel and through a shoulder 28

5 forged with or otherwise rigidly secured to said shaft, which fly-wheel is provided with the usual friction clutch 29, actuated by the coiled spring 30, the rear end of which 5 spring abuts against the clutch cover 31.

10 Bolted to a flange 32 projecting from the rim of the fly-wheel is a rear ring 33 for a rotary suction fan, opposed by its front ring 34, between which and the hub is an annular 15 opening or passage 35, the two rings being connected by means of vanes 36 located at frequent intervals of each other, as indicated in Fig. 6, and at such an angle with reference to the periphery of the rings that the 20 vanes will operate to suck the air from the engine and discharge it through the continuous circular opening between the edges of the rings, of which the rear ring 33 curves inwardly and the front ring 34, outwardly. 25 20 The form of the vanes, as shown in Fig. 3, is approximately that of the truncated sector of a circle, but may have other form, as, for instance, as shown in Fig. 2, wherein a rectangular vane is confined between flat 25 portions of both rings, but when the front and rear rings extend at an angle, the form 30 of the vane is polygonal.

For partially closing the front end of the 30 housing and inducing the passage of the heated air directly from the engine into the fan housing, there is secured to the flange 14 of the housing, by means of screws or rivets 37 (see Fig. 3) a collector 38 in the 35 form of an approximately truncated cone, the truncated end of which is mounted upon a post 39, to which it is secured by means of a screw 40, which post projects from the upper crank case, the lower edge of the collector being secured directly to the lower 40 crank case 41 by means of bolts 42.

Bolted to the usual bell 43 (see Fig. 6) 45 of the transmission housing and to the rear flange of the fan housing are angle plates 44, and to the side bars of the frame, angle 50 plates 45 for centering and stiffening the housing, but any other means suitable for these purposes may be employed.

The vehicle is provided with the usual 55 sheet metal hood 46, floor 47, foot board 48, dash-board 49, and drip pan 50, which pan is secured to the forward end of the frame 60 and to the fan housing by bolts 51, 51, at suitable intervals of each other.

Closing the space between the rear end 55 portion of the pan and the floor 47 of the vehicle is an approximately semicircular register 52, the inner edge of the fixed perforated plate 53 (see Fig. 3) for which is secured to the usual transmission housing 60 54 by bolts 55, to the drip pan by bolts 56, at suitable intervals for that purpose, and to the floor and sides of the body, respectively by bolts 56^a and 56^b (see Fig. 5).

To the fixed plate 53 are also secured, 65 adjacent the upper edge thereof, by the

bolts 55, approximately semicircular strips 57, opposed by a similar strip 57^a, by means of rivets 57^b, which said strips are angular in cross-section and provide a guideway for the perforated sliding plate 58 for the 70 register, which sliding member, for convenience of operation, is connected by a link 59 with a rod 60, projecting upwardly through the floor of the vehicle and connected at its upper end with an eye-bolt 61, 75 passing through an elongated slot 62 (see Fig. 5) in a slotted plate 63 of a register device, between which plate and the floor of the vehicle is the slotted, sliding plate of the register 64, to which the eye-bolt 61 is 80 fixed. The fixed grid 63 (see Fig. 5) is also provided with an elongated slot 65, through which projects a post 66, which is secured to the sliding grid 64 and provided at its 85 outer end with a handle 67, whereby the driver may open or close and adjust the register, to which, through a suitable opening in the floor, the heated air may freely 90 ascend into the body of the vehicle for supplying heat to the occupant.

In short, the register 52 is not only adapted for wholly or partly utilizing the hot air currents from the engine for supplying heat to the occupant of the vehicle, but for varying the quantity of the heated air from the 95 engine induced and distributed by the fan, and which it is desirable to vary to accord with the extremes of the surrounding atmosphere; as, for example, when extremely hot, the hot air should be freely drawn from the engine and from the machine. On the other hand, when very cold, such a rapid discharge of the heated air from the engine being unnecessary, it is then desirable to utilize as much hot air as possible for heating 100 the occupant of the vehicle.

It is now to be observed that the foot-board 48 is provided on its under-side with a baffle-plate 69, spaced from the foot-board at its bottom edge by a transverse bar 70 110 and intermediate its length by blocks 71, the side edges of the baffle-plate being provided with a flange (not shown) secured to the body of the vehicle. The function of the baffle-plate 69 is to insulate the foot-board 115 48 from the hot air directed by the fan for the greater comfort of the driver and also to discharge any heat that may accumulate between the baffle-plate and the foot-board and which is accomplished by means of perforations 72 through the dash-board 49.

In conclusion it is to be noted that, in confining the claims herein to the construction and support for the fan, the right is reserved to file a divisional application containing claims for other novel features herein described and shown in the drawings.

Having described my invention, what I claim and desire to secure by Letters Patent is:

1. A device for the purposes described, comprising in combination a fly-wheel, surrounding front and rear rings therefor, one of which is detachably secured to the fly-wheel, fan vanes connecting said rings together at intervals thereof, said front ring being bent to deflect towards the axis of the fan the air currents discharging therefrom. 40
- 5 2. A device for the purposes described, comprising in combination a fly-wheel, a fan, front and rear rings surrounding the fan detachably mounted upon the fly-wheel, said rings being bent to provide an outwardly curved passage adapted to direct said air to and discharge it from the fan in a plane approximately parallel with the axis of the fly-wheel. 50
- 10 3. A device for the purposes described, comprising in combination a fly-wheel, a fan, front and rear rings therefor, vanes connecting the rings at spaced intervals, said front ring being provided with an opening forming an annular passage surrounding the fly-wheel through which air currents are directed between the vanes of the fan. 55
- 15 4. A device for the purposes described, comprising in combination a fly-wheel, and a fan, including front and rear rings surrounding the fly-wheel, said rear ring being rigidly secured to the fly-wheel, vanes connecting said rings adapted to suspend the front ring from the rear ring, said front ring being provided with an opening forming an annular passage surrounding the fly-wheel for conducting the air currents directly into the fan, both of said rings being curved towards each other and thereby 60
- 20 5. A device for the purposes described, comprising in combination a fly-wheel, and a fan, including spaced curved rings surrounding and detachably secured to the fly-wheel, connected at frequent intervals of each other by the vanes of the fan, said front ring having an opening providing an annular space surrounding the fly-wheel, through which air currents are conducted directly into the fan and are thence discharged axially therefrom between said rings at an angle with reference to the sides of the fan. 65
- 25 6. A device for the purposes described, comprising in combination a fly-wheel, a fan, including front and rear rings mounted upon and surrounding the fly-wheel, and a rearwardly diverging housing adjacent to and surrounding said fan and rings. 70
- 30 7. A device for the purposes described, comprising in combination a fly-wheel, a fan, including front and rear rings mounted upon the fly-wheel, a housing surrounding said fan, and a fixed collector opposed to and projecting forward from said front ring. 75
- 35 8. A device for the purposes described, comprising in combination a fly-wheel, a fan including front and rear rings mounted upon the fly-wheel, a conical housing adjacent to and surrounding said fan and rings, and a fixed warped surface collector opposing and projecting forward from said front ring. 80

In witness whereof I have hereunto set my hand this 12th day of January, 1922.

ERNEST VAN TOFF.
